LIQUID DISPENSER

Kurt Kanno, Weil (Aspe), near Salzhausen, Germany

Application July 19, 1954, Serial No. 444,187

Claims priority, application Germany July 24, 1953

22 Claims. (Cl. 222—205)

This invention relates to liquid dispensers.

More particularly this invention relates to liquid dispensers enabling an operator to dispense a predetermined amount of liquid while using but one hand.

It is an object of this invention to provide a liquid dispenser enabling a dentist, or doctor, or laboratory technician to saturate a cotton wad with a liquid, while using but one hand.

It is another object of this invention to provide a liquid dispenser whereby the operator may insert a cotton wad in the mouthpiece of a liquid conduit and manipulate such conduit so as to cause liquid to flow therethrough thereby saturating the cotton wad.

It is still another object of this invention to provide a sanitary liquid dispenser enabling the operator to saturate a cotton wad with liquid without it being necessary on his part to touch or manipulate any portion of the dispenser.

It is also one of the objects of the present invention to provide a cover member for use in a liquid dispenser, the manipulation of which cover member changes the volume of and consequently the pressure within a container so as to cause liquid to be discharged through a suitable discharge conduit.

With the above objects in view the present invention mainly consists of a liquid dispenser comprising a container having an opening which opening is covered by a cover member. At least a portion of the cover member is flexible and has a vent aperture connecting the interior of the container with the exterior. A combined conduit and operating member is movably arranged on the cover member. The combined conduit and operating member has a conduit portion connecting the interior of the container with the exterior, which conduit portion extends throughout part of its length adjacent the outer end thereof substantially parallel to the liquid level of a liquid within the container. The inner end of the conduit portion is adapted to communicate with such liquid within the container and has at its outer end a funnel-shaped mouthpiece portion, the upper lip edge of which overlies the lower lip edge. The conduit portion also has an operating stud portion at a place intermediate the ends of the conduit portion and lying exterior of the container. The operating stud portion is opposite the vent aperture of the flexible portion of the cover member so that when the combined conduit and operating member is moved toward the flexible portion of the cover member the operating stud portion closes the vent aperture and flexes the flexible portion of the cover member so as to vary the volume of and consequently the pressure within the container thereby causing discharge of liquid through the conduit portion and mouthpiece portion of the combined conduit and operating member while the same is moved toward the flexible portion of the cover member. The cover member also carries guide means for guiding the movement of the combined conduit and operating member within a plane traversed by the flexible portion of the cover member. Spring means are connected to the cover

2

member and the combined conduit and operating member for urging the operating stud portion away from the flexible portion of the cover member. The cover member also carries a combined stop and positioning means for limiting the movement of the combined conduit and operating member toward the flexible portion of the cover member and for positioning the spring means with respect to the cover member and the combined conduit and operating member.

10 The novel features which are considered as characteristic for the invention are set forth in particular in the appended claims. The invention itself, however, both as to its construction and its method of operation, together with additional objects and advantages thereof, 15 will be best understood from the following description of specific embodiments when read in connection with the accompanying drawings, in which:

Fig. 1 is a cross-section of a liquid dispenser according to the present invention taken on line 1—1 of Fig. 2;

20 Fig. 2 is a plan view of the liquid dispenser illustrated in Fig. 1;

Fig. 3 is a partial side elevation, partly in section, taken along line 3—3 of Fig. 2;

25 Fig. 4 is a sectional view taken along line 4—4 of Fig. 2;

Fig. 5 is a side elevation, partly in section, of a modified combined conduit and operating member;

30 Fig. 6 is a partial side elevation, partly in section, of a modification of Fig. 1; and

Fig. 7 is a fragmentary showing similar to Fig. 6 shown on an enlarged scale.

Referring now to the drawing, and to Figs. 1 to 4 in particular, there is illustrated a liquid dispenser according to the present invention having a cup-shaped container 1 which may be made of glass or any other suitable material not affected by the action of a liquid to be dispensed. The container is closed by a cover member 2 which may be made of any suitable flexible material such as polyvinylchlorides, polyethylenes, such as polyamides, etc., which is likewise not affected by the action of a liquid contained with the container 1.

The cover member 2 has as an integral part thereof an apertured conduit member stud 3 through which passes a combined conduit and operating member 4. The combined conduit and operating member 4 has a vertical conduit portion extending through the apertured stud 3, the lower or inner end of the vertical conduit portion being in communication with the liquid which is to be dispensed. The combined conduit and operating member has a substantially horizontal conduit portion 5 and may be joined to the vertical conduit portion by a rounded conduit portion. As is shown in Fig. 1, the vertical, rounded and horizontal portions may be integral so as to form one continuous conduit portion. Alternatively, the vertical, rounded and horizontal portions may be made of separate pieces.

The right free end of the horizontal portion 5, as viewed in Fig. 1, constitutes the mouthpiece or outer end 6 of the combined conduit and operating member, and is funnel-shaped so that a cotton wad may readily be inserted into the funnel or cup 7. The upper lip edge 20 of the funnel-shaped mouthpiece overlies the lower lip edge so as to protect the mouthpiece against the introduction of foreign articles.

65 An operating stud portion 15 is carried by the horizontal portion 5 of the combined conduit and operating member for a purpose described below.

The combined conduit and operating member may be made of any suitable material such as glass, and the operating stud portion 15 may be fused thereto or otherwise suitably joined to be combined conduit and operating member.

The cover member 2 has a flexible membrane or diaphragm portion 8 having as a part thereof a stud 10. A vent aperture 9 passes through the stud whereby the interior of the container may be vented to atmosphere. The operating stud 15 of the combined conduit and operating member is adapted to engage the stud 10 and, while so engaging the stud, to close the aperture 9. It will be understood that the combined conduit and operating member is inherently sufficiently flexible so that when a downward force is applied to the mouthpiece end 6, the combined conduit and operating position will bend and the operating stud portion be moved toward the stud 10. It will also be understood that the cover member 2, since it is made of a flexible material, will, upon downward movement of the mouthpiece 6 deform slightly in the vicinity of the apertured conduit member stud 3. Consequently, the combined conduit and operating member will be able to pivot about the stud 3 if there is insufficient inherent resilience in the rounded conduit portion joining the vertical and horizontal conduit portions.

The cover member 2 carries guide posts 11 and 12 for guiding the movement of the combined conduit and operating member within a plane traversed by the flexible portion 8 of the cover member 2. As is best seen in Figs. 2 and 3, the guide posts are spaced apart a distance substantially equal to the outside diameter of the horizontal conduit portion 5 so as to prevent lateral movement of the latter and to limit the movement thereof to a substantially vertical plane.

A stop member 13 is located between the guide posts 11 and 12 and limits the downward movement of the horizontal conduit portion 5. A compression spring 14 is interposed between the cover member 2 and the horizontal conduit portion 5 so as to urge the latter away from the cover member, thereby urging the operating stud portion 15 away from the apertured stud 10. As is seen in Figs. 1, 2 and 3, the spring 14 is substantially concentric with the stop 13 so that the latter also acts as a positioning means for the spring 14.

The cover member 2 also has a filler opening stud 17 adapted to receive a stopper 16, shown in Fig. 4. In this way it is possible to fill the container 1 through the opening afforded by the stud 17 without it being necessary to remove the cover 2 from the container 1.

The operation of the dispenser is as follows:

When the operator desires to obtain a certain amount of liquid he depresses the mouthpiece end 6 of the combined conduit and operating member. This may be accomplished by inserting a wad of cotton, held by pincers, into the funnel-shaped mouthpiece end of the combined conduit and operating member. The combined conduit and operating member is then moved against the bias of the spring 14 whereby the operating stud portion 15 is brought to bear against the apertured stud 10 of the cover member 2. The stud 10 forms a valve seat and the operating stud portion 15 constitutes a valve so that when the operating stud portion 15 is brought into contact with the stud 10 the operating stud portion 15 closes the aperture 9. When the operating stud portion 15 is then further moved downwardly the flexible portion 8 of the cover member 2 flexes inwardly so as to decrease the volume of the space within the container 1 above the liquid level of a liquid contained therein, and consequently the pressure within that space is increased. As the flexible portion 8 is flexed inwardly and as the pressure within the container 8 is increased, liquid rises through the vertical conduit portion of the combined conduit and operating member and passes through the rounded conduit portion and the horizontal portion 5 into the funnel-shaped mouthpiece end of the combined conduit and operating member. The wad of cotton will then absorb the liquid and is withdrawn from the mouthpiece end of the combined conduit and operating member. The spring 14 will thereupon urge the combined conduit and operating member away from the cover member 2 and the operating

stud portion 15 will be urged away from the stud 10 so as to uncover the aperture 9 and atmospheric pressure will be restored to the space within the container 1 above the liquid level.

5 The stop 13 limits the downward movement of the operating stud portion 15 so that a certain predetermined amount of liquid will be forced through the conduit portion of the combined conduit and operating member 15. If it is desired to pass more than such predetermined amount of liquid through the conduit portion the upward and downward movement of the combined conduit and operating member may be repeated as desired.

A modified combined conduit and operating member 4^A having a differently shaped mouthpiece or outer end

15 6^A is shown in Fig. 5. The combined conduit and operating member has a horizontal conduit portion 5^A and operating stud portion 15^A corresponding to the conduit portion 5 and the operating stud portion 15 of the combined conduit and operating member illustrated in Fig. 1.

20 The upper lip edge 20^A of the mouthpiece overlies the lower lip edge so as to protect the mouthpiece against the introduction of foreign particles. The mouthpiece of the combined conduit and operating member of Fig. 5 differs from that of Fig. 1 in that the approximate center

25 axis of the funnel-shaped mouthpiece is inclined slightly upwardly with respect to the liquid level of a liquid within the container 1. By virtue of such an arrangement any excess liquid not absorbed by a cotton wad will flow back readily into the container after the termination of

30 the dispenser operation.

It will be understood that the mouthpiece portion of the combined conduit and operating members illustrated in Figs. 1 and 5 may either be integral with the respective horizontal conduit portions or may be separate members

35 suitably joined thereto.

The cover member 2 may be molded or formed by injection molding or by injection die-casting. The cover member when so produced may include as integral parts thereof the filler opening stud 17, the apertured conduit

40 member stud 3, the guide posts 11 and 12, the combined stop and positioning member 13, as well as the flexible portion 8, together with the apertured stud 10 thereof.

It will be understood, therefore, that the assembling of a dispenser according to the present invention is extremely simple. After the spring 14 is placed over the positioning member 13 and the combined conduit and operating member is inserted through the stud 3, the resulting cover assembly is then placed on the container 1. The container may be filled with a liquid to be dispensed 45 either before the cover assembly is placed thereon or may be filled through the stud 17 after the cover assembly has been mounted onto the container. The stopper 16 is then inserted into the stud 17 so as to close the container.

50 Figs. 6 and 7 illustrate a modification of the dispenser shown in Figs. 1 to 5. A cover member 2' having a dome-shaped flexible portion 21 is mounted on a container 1'. The flexible portion 21 has a vent aperture 9' reinforced by an annular ring 22. A dispenser according 55 to this embodiment includes a movably mounted combined conduit and operating member 4' having a horizontal conduit portion 5' and a mouthpiece portion 6'. The movement of the combined conduit and operating member 4' is guided by guide posts 11' and 12' (not shown).

The operating stud portion 15 of the combined conduit and operating member 4 of Fig. 1 is replaced by an actuating member having an actuating portion 23 which is movably arranged on the cover member 2' for movement between the combined conduit and operating member 4' and the vent aperture 9' of the flexible portion 21 of the cover member 2'. The actuating portion 23 is connected to an inherently resilient intermediate portion 24 which, in turn, is connected to a base portion 26 having 60 a peg 25. The actuating member is preferably an inte-

gral piece made of a material unaffected by the liquid to be dispensed.

The cover member 2' has as a part thereof a boss 13' which has a groove adapted to receive the peg 25 of the actuating member. The actuating member may be mounted on the cover member 2' by inserting the peg 25 of the base portion 26 into the groove of the boss 13'.

A spring 27 is connected to the boss 13' and biases the actuating portion 23 away from the aperture 9' and toward the horizontal conduit portion 5' of the combined conduit and operating member 4'.

The actuating portion 23 cooperates with the ring 22 so as to close the aperture 9' when the actuating portion is in contact with the ring 22.

The operation of a dispenser according to this embodiment is identical to the operation of the dispenser illustrated in Figs. 1 to 5. When the mouthpiece end 6' of the combined conduit and operating member is moved downwardly the horizontal conduit portion engages the actuating portion 23 so that the latter first closes the aperture 9' and then flexes the flexible portion 21 downwardly so as to decrease the volume of and consequently increase the pressure within the container 1'. Liquid will then flow through the combined conduit and operating member, as set forth above.

It will be understood that each of the elements described above, or two or more together, may also find a useful application in other types of liquid dispensers differing from the types described above.

While the invention has been illustrated and described as embodied in a liquid dispenser making use of a single combined conduit and operating member, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A liquid dispenser comprising, in combination, a closed container; pump means associated with said container for varying the pressure therein; and a combined conduit and operating member for placing the interior of said container in communication with the exterior thereof, said combined conduit and operating member being mounted on said container for pivotal movement relative thereto and operatively associated with said pump means for operating the latter when said combined conduit and operating member is pivoted relative to said container thereby causing discharge of liquid through said combined conduit and operating member while the same is pivoted relative to said container.

2. A liquid dispenser comprising, in combination, a container having an opening; a cover member covering said opening so as to close said container; pump means associated with said cover member for varying the pressure within said container; and a combined conduit and operating member for placing the interior of said container in communication with the exterior thereof, said combined conduit and operating member being mounted on said cover member for pivotal movement relative thereto and operatively associated with said pump means for operating the latter when said combined conduit and operating member is pivoted relative to said cover member thereby causing discharge of liquid through said combined conduit and operating member while the same is pivoted relative to said cover member.

3. A liquid dispenser, comprising, in combination, a container having an opening; a cover member covering said opening so as to close said container, at least a portion of said cover member being flexible, said flexible portion also covering said opening so that flexing of said flexible portion varies the volume of and consequently the pressure within said container; and a combined conduit and operating member for placing the interior of said container in communication with the exterior thereof, said combined conduit and operating member being mounted on said cover member for pivotal movement relative thereto and operatively associated with said flexible portion of said cover member for flexing the latter when said combined conduit and operating member is pivoted relative to said flexible portion of said cover member so as to flex the latter, whereby liquid is discharged through said combined conduit and operating member while the same is pivoted relative to said cover member.

4. A liquid dispenser, comprising, in combination, a container having an opening; a cover member covering said opening so as to close said container, at least a portion of said cover member being flexible; and a combined conduit and operating member movably arranged on said cover member, said combined conduit and operating member having a conduit portion connecting the interior of said container with the exterior, the inner end of said conduit portion being adapted to communicate with a liquid within said container and said container portion having at its outer end a mouthpiece portion, and having also an operating stud portion at a place intermediate the ends of said conduit portion and opposite said flexible portion of said cover member, so that when said combined conduit and operating member is moved relative to said flexible portion of said cover member, said operating stud portion of said combined conduit and operating member flexes said flexible portion of said cover member so as to vary the volume of and consequently the pressure within said container thereby causing discharge of liquid through said conduit portion and mouthpiece portion of said combined conduit and operating member while the same is moved relative to said flexible portion of said cover member.

5. A liquid dispenser, comprising, in combination, a container having an opening; a cover member covering said opening so as to close said container, at least a portion of said cover member being flexible; and a combined conduit and operating member movably arranged on said cover member, said combined conduit and operating member having a conduit portion connecting the interior of said container with the exterior, the inner end of said conduit portion being adapted to communicate with a liquid within said container and said conduit portion having at its outer end a mouthpiece portion, and having also an operating stud portion at a place intermediate the ends of said conduit portion exterior of said container and opposite said flexible portion of said cover member, so that when said combined conduit and operating member is moved toward said flexible portion of said cover member, said operating stud portion of said combined conduit and operating member flexes said flexible portion of said cover member so as to vary the volume of and consequently the pressure within said container thereby causing discharge of liquid through said conduit portion and mouthpiece portion of said combined conduit and operating member while the same is moved toward said flexible portion of said cover member.

6. A liquid dispenser, comprising, in combination, a container having an opening; a cover member covering said opening so as to close said container, at least a portion of said cover member being flexible; a combined conduit and operating member movably arranged on said cover member, said combined conduit and operating member having a conduit portion connecting the interior of said container with the exterior, the inner end of said

conduit and operating member flexes said flexible portion of said cover member so as to vary the volume of and consequently the pressure within said container thereby causing discharge of liquid through said conduit portion and mouthpiece portion of said combined conduit and operating member while the same is moved relative to said flexible portion of said cover member.

12. A liquid dispenser, comprising, in combination, a container having an opening; a cover member covering said opening so as to close said container, at least a portion of said cover member being flexible; and a combined conduit and operating member movably arranged on said cover member, said combined conduit and operating member having a conduit portion connecting the interior of said container with the exterior, said conduit portion being inclined throughout at least part of its length slightly upwardly with respect to the liquid level of a liquid within said container, the inner end of said conduit portion being adapted to communicate with the liquid within said container and said conduit portion having at its outer end a mouthpiece portion, and having also an operating stud portion at a place intermediate the ends of said conduit portion and opposite said flexible portion of said cover member, so that when said combined conduit and operating member is moved relative to said flexible portion of said cover member, said operating stud portion of said combined conduit and operating member flexes said flexible portion of said cover member so as to vary the volume of and consequently the pressure within said container thereby causing discharge of liquid through said conduit portion and mouthpiece portion of said combined conduit and operating member while the same is moved relative to said flexible portion of said cover member.

13. A liquid dispenser, comprising, in combination, a container having an opening; a cover member covering said opening so as to close said container, at least a portion of said cover member being flexible; and a combined conduit and operating member movably arranged on said cover member, said combined conduit and operating member having a conduit portion connecting the interior of said container with the exterior, said conduit portion extending throughout part of its length adjacent the outer end thereof substantially parallel to the liquid level of a liquid within said container, the inner end of said conduit portion being adapted to communicate with the liquid within said container and said conduit portion having at its outer end a funnel-shaped mouthpiece portion, the upper lip edge thereof overlying the lower lip edge thereof, and having also an operating stud portion at a place intermediate the ends of said conduit portion and opposite said flexible portion of said cover member, so that when said combined conduit and operating member is moved relative to said flexible portion of said cover member, said operating stud portion of said combined conduit and operating member flexes said flexible portion of said cover member so as to vary the volume of and consequently the pressure within said container thereby causing discharge of liquid through said conduit portion and mouthpiece portion of said combined conduit and operating member while the same is moved relative to said flexible portion of said cover member.

14. A liquid dispenser, comprising, in combination, a container having an opening; a cover member covering said opening so as to close said container, at least a portion of said cover member being flexible; a combined conduit and operating member movably arranged on said cover member, said combined conduit and operating member having a conduit portion connecting the interior of said container with the exterior, the inner end of said conduit portion being adapted to communicate with a liquid within said container and said conduit portion having at its outer end a mouthpiece portion, and having also an operating stud portion at a place intermediate the ends of said conduit portion exterior of said container and opposite said flexible portion of said cover member, so that when

said combined conduit and operating member is moved toward said flexible portion of said cover member, said operating stud portion of said combined conduit and operating member flexes said flexible portion of said cover member so as to vary the volume of and consequently the pressure within said container thereby causing discharge of liquid through said conduit portion and mouthpiece portion of said combined conduit and operating member while the same is moved toward said flexible portion of said cover member; and stop means carried by said cover member for limiting the movement of said combined conduit and operating member toward said flexible portion of said cover member.

15. A liquid dispenser, comprising, in combination, a container having an opening; a cover member covering said opening so as to close said container, at least a portion of said cover member being flexible; a combined conduit and operating member movably arranged on said cover member, said combined conduit and operating member having a conduit portion connecting the interior of said container with the exterior, the inner end of said conduit portion being adapted to communicate with a liquid within said container and said conduit portion having at its outer end a mouthpiece portion, and having also an operating stud portion at a place intermediate the ends of said conduit portion exterior of said container and opposite said flexible portion of said cover member, so that when said combined conduit and operating member is moved toward said flexible portion of said cover member, said operating stud portion of said combined conduit and operating member flexes said flexible portion of said cover member so as to vary the volume of and consequently the pressure within said container thereby causing discharge of liquid through said conduit portion and mouthpiece portion of said combined conduit and operating member while the same is moved toward said flexible portion of said cover member; and stop means carried by said cover member for guiding the movement of said combined conduit and operating member within a plane traversed by said flexible portion of said cover member; spring means connected to said cover member and said combined conduit and operating member for urging said operating stud portion of said combined conduit and operating member away from said flexible portion of said cover member; and combined stop and positioning means carried by said cover member for limiting the movement of said combined conduit and operating member toward said flexible portion of said cover member and for positioning said spring means with respect to said cover member and said combined conduit and operating member.

16. A liquid dispenser, comprising, in combination, a container having an opening; a cover member covering said opening so as to close said container, at least a portion of said cover member being flexible; a combined conduit and operating member movably arranged on said cover member, said combined conduit and operating member having a conduit portion connecting the interior of said container with the exterior, the inner end of said conduit portion being adapted to communicate with a liquid within said container and said conduit portion having at its outer end a mouthpiece portion; and an actuating member movably arranged on said cover member for movement between said combined conduit and operating member and said flexible portion of said cover member, so that when said combined conduit and operating member is moved toward said flexible portion of said cover member, said actuating member flexes said flexible portion of said cover member so as to vary the volume of and consequently the pressure within said container thereby causing discharge of liquid through said conduit portion and mouthpiece portion of said combined conduit and operating member while the same is moved toward said flexible portion of said cover member.

17. A liquid dispenser, comprising, in combination, a

container having an opening; a cover member covering said opening so as to close said container, at least a portion of said cover member being flexible, said flexible portion having a vent aperture connecting the interior of said container with the exterior; a combined conduit and operating member movably arranged on said cover member, said combined conduit and operating member having a conduit portion connecting the interior of said container with the exterior, the inner end of said conduit portion being adapted to communicate with a liquid within said container and said conduit portion having at its outer end a mouthpiece portion; and an actuating member movably arranged on said cover member for movement between said combined conduit and operating member and said vent aperture of said flexible portion of said cover member, so that when said combined conduit and operating member is moved toward said flexible portion of said cover member, said actuating member closes said vent aperture of said flexible portion and flexes said flexible portion of said cover member so as to vary the volume of and consequently the pressure within said container thereby causing discharge of liquid through said conduit portion and mouthpiece portion of said combined conduit and operating member while the same is moved toward said flexible portion of said cover member.

18. In a liquid dispenser comprising a container having pump means associated therewith for varying the pressure within the container, a cover member, at least a portion of said cover member being flexible and adapted to vary the volume of and consequently the pressure within the container, said cover member having an apertured stud adapted to receive a conduit member passing through said cover member, said cover member also having at least one guide member adapted to guide the movement of the pump means, and said cover member also having a combined stop and positioning member adapted to limit the movement of the pump means and to position biasing means adapted to cooperate with the pump means.

19. In a liquid dispenser comprising a container having pump means associated therewith for varying the pressure within the container, a cover member, at least a portion of said cover member being flexible and adapted to vary the volume of and consequently the pressure within the container, said cover member having an apertured filler opening stud adapted to receive a stopper, said cover member also having an apertured conduit member stud adapted to receive a conduit member passing through said cover member, said cover member also having at least one guide member adapted to guide the movement of the pump means, and said cover member also having a combined stop and positioning member adapted to limit the movement of the pump means and to position biasing means adapted to cooperate with the pump means.

20. In a liquid dispenser comprising a container having a flexible portion and an operating member co-operating with a said flexible portion of the container so as to vary the volume of and consequently the pressure within the container, an actuating member having an actuating portion between the operating member and the flexible portion of the container and adapted to flex the latter when moved by the former, an intermediate portion connected to said actuating portion, and a base portion connected to said intermediate portion, said actuating member being connected at said base portion thereof to the liquid dispenser.

21. A liquid dispenser comprising, in combination, a container having an opening; a cover member covering said opening so as to close said container, at least a

portion of said cover member being flexible, said flexible portion having a vent aperture connecting the interior of said container with the exterior; a combined conduit and operating member movably arranged on said cover member, said combined conduit and operating member having a conduit portion connecting the interior of said container with the exterior, said conduit portion extending throughout part of its length adjacent the outer end thereof substantially parallel to the liquid level of a liquid within said container, the inner end of said conduit portion being adapted to communicate with a liquid within said container and said conduit portion having at its outer end a funnel-shaped mouthpiece portion, the upper lip edge thereof overlying the lower lip edge thereof, and also having an operating stud portion at a place intermediate the ends of said conduit portion exterior of said container and opposite said vent aperture of said flexible portion of said cover member, so that when said combined conduit and operating member is moved toward said flexible portion of said cover member, said operating stud portion of said combined conduit and operating member closes said vent aperture of said flexible portion and flexes said flexible portion of said cover member so as to vary the volume of and consequently the pressure within said container thereby causing discharge of liquid through said conduit portion and mouthpiece portion of said combined conduit and operating member while the same is moved toward said flexible portion of said cover member; guide means carried by said cover member for guiding the movement of said combined conduit and operating member within a plane traversed by said flexible portion of said cover member; spring means connected to said cover member and said combined conduit and operating member for urging said operating stud portion of said combined conduit and operating member away from said flexible portion of said cover member; and combined stop and positioning means carried by said cover member for limiting the movement of said combined conduit and operating member toward said flexible portion of said cover member and for positioning said spring means with respect to said cover member and said combined conduit and operating member.

22. A liquid dispenser, comprising, in combination, a closed container; pump means associated with said container for varying the pressure therein; and a combined conduit and operating member mounted on said container for simultaneous pivot movement relative thereto and substantially reciprocating movement relative to said pump means for placing the interior of said container in communication with the exterior thereof and for operating said pump means when said combined conduit and operating member reciprocates relative thereto whereby when said combined conduit and operating member is pivoted relative to said container said combined conduit and actuating member reciprocates relative to said pump means thereby operating the same and causing the discharge of fluid through said combined and operating member while the same is pivoted relative to said container.
